(57) **CLAIM**

The ornamental design for “A Computer with a Wrap Around Display,” as shown and described.

DESCRIPTION

FIG. 1 is a front, right perspective view of a bottom of a computer in a closed position. The side panels of the display are folded around the base of the computer.

FIG. 2 is a top view of the computer of FIG. 1.

FIG. 3 is a bottom view of the computer of FIG. 1.

FIG. 4 is a front view of the computer of FIG. 1.

FIG. 5 is a rear view of the computer of FIG. 1.

FIG. 6 is a top, front, right perspective view of the computer of FIG. 1 in a first open position with the side panels in a fully unfolded position.

FIG. 7 is a top view of the computer of FIG. 6.

FIG. 8 is a bottom view of the computer of FIG. 6.

FIG. 9 is a front view of the computer of FIG. 6.

FIG. 10 is a rear view of the computer of FIG. 6.

FIG. 11 is a top, front, right perspective view of the computer of FIG. 1 in a second open position with the side panels of the display slightly folded.

FIG. 12 is a top view of the computer of FIG. 11.

FIG. 13 is a bottom view of the computer of FIG. 11.

FIG. 14 is a front view of the computer of FIG. 11; and,

FIG. 15 is a rear view of the computer of FIG. 11.

The broken lines and surfaces between the broken lines show portions of the computer with a wrap around display that form no part of the claimed design.
